HOOD HINGE AND LATCH MECHANISM

Edward T. Ragsdale and Edward F. Reynolds,
Flint, Mich., assignors to General Motors Corporation, Detroit, Mich., a corporation of Delaware

Application May 13, 1940, Serial No. 334,742

3 Claims. (Cl. 16—128.1)

This invention relates to latches for the hood doors of the hoods of automotive vehicles.

The hood door of the vehicle is made of one piece and is adapted to hinge from either side. The latches at each side are duplicates, the one of the other, and by releasing the latch mechanism on one side the latch mechanism at the opposite side serves as a hinge for the hood door when the door is raised.

The novelty of the invention relates to details of construction of the latch structure.

On the drawings:

Figure 1 is a side view of the hood of an automotive vehicle showing the hood door in raised position in dotted outline.

Figure 2 is a section on the line 2—2 of Figure 1, showing the hood door in raised position in dotted outline.

Figure 3 is a plan view of the latching mechanism showing the parts in released position and with the hood broken away better to show the construction. The handle is shown in dotted outline in the latching position of the parts.

Figure 4 is a section on the line 4—4 through one of the latching mechanisms, the raised position of the hood being shown in dotted outline.

Figure 5 is a perspective view of the latching mechanism.

Figure 6 is a side view of an alternative form of latching mechanism with parts broken away better to show details of construction and the right hand latch only being shown.

Figure 7 is a section on the line 7—7 of Figure 6.

Figure 8 is a detailed plan view of a part of the latching mechanism;

Figures 9 and 10 are sections on the lines 9—9 and 10—10 of Figure 6.

Figure 11 is a view of a modification showing the application of a safety catch.

Figure 12 is a side view of a modified form of latch mechanism, parts being broken away better to show details of construction and the right hand latch only being shown.

Figures 13, 14, and 15 are sections on the corresponding lines of Figure 12.

Referring to the drawings, an automotive vehicle is indicated as a whole at 2. The vehicle has the usual windshield 4, cowl 6, hood side or fender 8, hood door 10, and side panels 12 which separate the engine compartment from the hood side or the fender. The usual grillework for the entrance of the air at the front of the vehicle is indicated at 14. The parts so far described are

in general conventional and per se form no part of the invention.

The handle for operating the latch is indicated at 16. This handle projects away from the upright part of the fender but may be made a part of the usual side louvers of the hood as is well known in the art.

In its raised position the hood door 10 is supported by the links 18 and 20, the link 18 being pivoted at 22 to the underside of the hood and the link 20 pivoted at 24 to the front end of the cowl or usual dashboard 26. Two sets of links 18 and 20 are provided, one at each side of the hood door.

Referring to Figure 5, the hood door 10 is provided around its edge with a lateral inturned flange 28 and at spaced apart places at the angle between the flange 28 and the hood door 10, brackets 30 are rigidly secured.

The side panels 12 at their upper edges have inturned flanges 32 and downturned flanges 34, while the edge of the vertical part of the fender 8 overlaps the flanges 32 and 34 and has corresponding flanges 36 and 38 so that a double thickness of metal is formed at the upper edge of the engine compartment. The flange 28 on the hood door is adapted to fit over the flange 36 with the edge of the door coinciding with the plane of the fender 8 so that a smooth contour is obtained. This is best shown in Figures 4 and 5.

The handle 16 is pivoted by the pin 40 to brackets 46 secured to the panel 12 of the engine compartment. The handle extends inwardly of the hood and has an enlarged end 48 which has two openings therein. In the openings there are received the bent ends of the rods 50 and 52 which extend from the handle in opposite directions adjacent the side of the hood.

Referring to Figure 5, it will be seen that a bracket 54 is secured to the panel 12 and to the flanges 36 and 38 of the fender edge. This bracket is secured at a place where it will mate with a bracket 30 secured to the underside of the hood. The bracket 54 has the upper flange 56 secured to the flange 36, the lower inturned flange 58, and the end flange 60 which is secured to the inside of the panel 12.

Suitable ears 62 are bent from the middle part of the bracket away from the plane thereof and are provided with suitable openings to receive a pivot bolt 64 which pivotally secures in place a movable bracket 66. The bracket has the lower ear 68 and the upper ear 70 which are positioned on top of the ears 62. The ears 68 and 70 have openings which mate with the openings in the ears 62, and a pivot pin 64 passes through all

these openings to pivot the bracket 66 on the bracket 54. A coil spring 72 surrounds the pivot pin or bolt 64 between the upper ear 62 and the ear 68 and provides the tension or force which holds the hood door down.

The upper end of the bracket 66 beyond the ear 70 is formed into a hook 74 the point 76 of which is adapted to engage on the bracket 30 to hold the hood in latched position.

The bracket 30 is provided with a rib or protuberance 78 at its edge over which the point 76 must pass in moving to latched position. This rib 78 will prevent any ordinary tendency of the hook end 76 to move away from contact with the bracket 30.

A pilot or stud 80 is secured to the bracket 54 by the nut 55. This pilot is tapered and somewhat rounded as is best shown in Figure 5, and is adapted to be received in an opening formed in the bracket 30. This opening has the raised flange 82 therearound to give it added strength and the pilot 80 is provided with a shoulder 84 against which the edge of the flange 82 is adapted to engage when the latch mechanism at the opposite side is released to enable the hood to be raised. The contact of the edge of the flange 82 with the shoulder 84 will limit the upward movement of the opposite hood side and will in general coincide with the position of the links 18 and 20 as shown in the dotted line position at the left of Figure 2.

If desired, the stud 80 may be secured to the bracket 30 and projects into an opening in the double flange part 32, 36.

Each side of the hood has two mechanisms such as shown in Figure 5, and these mechanisms are at the ends of the hood door and are operable from the common handle 16. To assure the operation of the mechanisms the ends of the rods 50 and 52 have bent ends 86 which engage in openings in ears 88 formed on a small piece of metal 90 secured to the movable bracket 66.

By moving the handle 16 from the dotted line position of Figure 3 to the full line position, the hook ends 76 are swung over the rib 78 clear of the bracket 30. The flange 28 of the hood has a cut-out 92 to assure that the hook end will not engage with the flange when moved to unlatched position. In the unlatched position, as shown in Figure 3, the hood door 10 at this side of the vehicle may be raised, and the hook ends 76 at the opposite side of the vehicle in cooperation with the studs 80 and flanges at 82 will form the hinge upon which the hood swings. The upward movement of the door will be limited by the straight line position of the links 18 and 20 and by the contact of the flange 82 with the shoulder 84. This contact of the flange 82 with the shoulder 84 is shown in dotted outline in Figure 4.

Referring to Figure 6, the second species of the invention is shown. The handle 16' is turnably mounted in a bushing 100 rigidly secured in the side panel 12. To the inner end of this handle there is secured the two-armed plate 102 in each end of which there is an opening. One end of the plate has an extension 104 which engages with a finger 106 formed on an angle bracket 108 secured to the panel 12. The purpose of this extension 104 and finger 106 is to limit the throw of the plate 102. In the position shown in Figure 6, the parts are in the hood latched position. A spring 110, secured to the bracket 108, retains the parts in position shown in Figure 6.

In each of the openings in the plate 102 there is secured the bent end of one of the rods 112

and 114. These rods extend in opposite directions and have their ends formed into a loop indicated as a whole at 116. The loop is in general U-shaped, but at the ends of the U has the bends 118 and 120 which project toward each other and form a narrow neck, and in the latched position of the hood, as shown in full lines in Figure 6, the bight 122 of the U is sprung apart so that the bend or protuberance 120 will tightly grip into the cup or pocket 123 formed in an angle bracket 124 which is secured to the edge of the hood door and to the flange 28.

A pilot or stud 126 is secured by means of the nut 128 to the bracket 124 and flange 28 and projects into an opening in the overlapping flanges 32 and 36 of the panel 12 and fender 8. This pilot is pointed and rounded and has the shoulder 130 which engages with the underside of the flange 32 when the hood is fully raised from the opposite side. If desired, the pilot 126 may be secured to the flanges 32 and 36 in the manner shown in Figure 5.

Immediately beyond the end of the bracket 124 the flange 28 of the hood has the cut away part 132 and adjacent the cut away part 132 the mating flanges 32 and 36 are provided with a slot indicated as a whole at 134. The initial part 136 of the slot is straight, the intermediary part 138 is at an angle, and the terminal part 140 is again straight, or in a plane parallel with the part 136. As the operator turns the handle 16' in the bearing 100 the plate 102 will push the arms 112 and 114 in opposite directions to cause the loop 116 to move from the full line position of Figure 6 to the dotted line position. In this movement the bight 122 of the loop will be guided by the slot 134 for the reason that the free end of the loop is passed through the slot. The reason for the slot 136, 138 and 140 is that it guides the loop away from the flange 28 and prevents the loop from falling out of the slot. In moving from the full line position to the dotted line position the loop will be moved out of the depression 123 and away from the flange 28 and will leave the hood door edge on that side unlatched so that the door may be raised from that side, while the latching mechanism at the opposite side of the hood door will act as the hinge.

The end of the loop 116 is upturned as indicated at 142 to enable the loop end easily to ride over the end of the bracket 124 when it is moved from unlatched to latched position.

The mechanism at the end of the rod 114 is identical with that shown and described in Figures 6 to 10 inclusive.

If desired, a strengthening plate 144 may be secured to the overlapping top flanges 32 and 36 of the hood side immediately below the place of application of the bracket 124 to the hood door. This plate will have an opening to accommodate the pilot 126.

In Figure 11 a modification of the structure of Figures 6-10 inclusive is shown. The modification consists in making the handle 16'' shiftable as well as turnable in its bearing 100''. A bracket 150 is secured to the panel 12 and the overlapping edges 32 and 36 and the bearing 100'' is secured between the panel 12 and the bracket. A catch 152 is pivoted at 154 to the bracket 150. The hook end 156 of the catch is adapted to engage with the flange 28 on the hood door 10 when in latched position. A spring 158 tends to hold the catch 152 in full line position shown in Figure 11. By pressing the handle 16'' first inward-

ly, the catch 152 is moved from the full line position to the dotted line position to cause its hook end 156 to become disengaged from the flange 28 on the hood door. The handle may then be rotated to turn the bearing 100 to move the rods 112 and 114 to operate the latching mechanism in the same manner as in connection with the structure of Figure 6.

Referring to Figures 12-15 inclusive, a third species is shown. The panel 12 has a shoulder 160 formed therein and on this shoulder there are mounted the two end brackets 162 and the center bracket 164. Only one of the end brackets 162 is shown for the reason that the structure at the right-hand end of Figure 12 is duplicated at the other end. In these brackets 162, 164 a shaft 166 is turnably mounted.

Adjacent the bracket 164 a lever 168 has one end 170 rigidly secured to the rod 166 and the other end formed into ears 172. Between the ears there is received the inner end 174 of a push rod 176, and a pivot pin 177 passes through the ears 172 and the end 174 pivotally to mount the parts 168 and 176. The outer end of the operating rod 176 has a knob 178, and a rubber dome 180 surrounds the rod 176 and has one end 182 secured to the fender 8 and its other end 184 inturned to catch under the knob 178. By pressing inwardly on the knob 178 the rubber dome 180 will yield and the rod 176 will be moved to operate the lever 168 to turn the shaft or rod 166.

At each end of the shaft 166, adjacent the brackets 162, an arm 186 is rigidly mounted. The free end 188 of the arm is shaped as is shown in the plan view in Figure 14.

The side panel 12 has a recess 190 formed therein (Figure 15) and in this recess there is received the nut 192 into which there is screwed one end of a stud 194. The stud 194 passes through a spacer 196 and through an opening 198 in the arm 186. The other end of the stud 194 is threaded and receives a nut and washer 200, and a coil spring 202 is positioned between the washer and the arm 186. This spring is under compression and constantly urges the arm to the position shown in Figure 15, or in the latched position of the hood.

The hood door 10 has a hinge, indicated generally at 204, secured thereto immediately over the place where the arms 186 are positioned. One part 206 of the hinge is rigidly secured to the hood door and the other part 208 projects inwardly of the hood and extends over the upper edge of the fender 8 and the panel 12. The part 208 of the hinge has a lug 210 which strikes against the hinge part 206 and prevents the hinge part 208 from moving closer to the part 206 than is shown in the position of the parts indicated in Figure 15. The hinge parts 206 and 208 are provided with small fingers 210' and 212 and between these fingers the coil springs 214 are secured. The springs are under tension and constantly tend to hold the parts in the position shown in Figure 15. The two hinged parts 206 and 208 are united by the pintle 216.

A pilot or stud 218 is secured by means of a nut 220 to the part 208 of the hinge. This pilot is cylindrical for a portion of its length and projects into the bushing 222 rigidly secured to the top edge flanges 32 and 36 of the panel 12 and fender 8.

Through the pilot 218 there passes a bolt 224 the head 226 of which is closely adjacent the turned over end 188 of the arm 186. A lock nut 75

228 prevents the bolt 224 from turning when it is once in its properly adjusted position.

In the latched position of the hood, as shown in Figure 15, the turned over end 188 engages the head 226. To facilitate a better engagement the end 188 is provided with an arcuate cut-out 230 to receive the shank of the bolt 224.

To release one side of the hood door 10 so that it may be raised, the operator presses on the knob 178 which depresses the rubber dome 180 and causes the lever 168 to rotate the shaft 166. The rotation of the shaft 166 will swing the arms 186 and compress the springs 202 and move the free end 188 away from the head 226 of the bolt 224 to release the hood on that side. The hood door may now be raised, causing the pilots 218 to move out of their bushings 222 and utilizing the hinge members 208 and 206 at the opposite side of the vehicle as the hinge upon which the hood door turns. In opening the hood the springs 214 at the opposite side of the vehicle will be further tensioned but the hood will swing on the pintles 216.

The species of Figures 7-11 inclusive and 12-15 inclusive are provided with links 18 and 20 such as shown in Figure 2.

The pilots in all of the species act to position the door accurately on the hood sides, that is, on the edge of the vertical part 8 of the fender.

We claim:

1. In a latch for the hood door of an automotive vehicle, a stationary part of the vehicle on which the door rests in closed position, an inwardly directed flange at each side edge of the hood door where it rests on the stationary part of the vehicle, a plurality of brackets spaced longitudinally of the hood at each side thereof and inside the vehicle and mounted on said stationary part, a second plurality of brackets, one of each of said second brackets pivoted to one of the first brackets, a hook on each of the second brackets capable of engaging the flange to hold the door in latched position, means at each side of the hood and inside thereof and operable from outside the vehicle simultaneously to move all the pivoted brackets at one side to cause the hooks to move out of contact with the flange to enable the hood door to be raised from one side.

2. In a latching mechanism for the hood door of an automotive vehicle, a stationary part of the vehicle on which the door rests in closed position, an inwardly directed flange at each side edge of the hood door where it rests on the stationary part of the vehicle, four brackets mounted in spaced relation inside the vehicle on the sides of said stationary part, two brackets being mounted at each side, a bracket pivoted to each of the first mentioned brackets, a hook on each one of the pivoted brackets, said hooks capable of engaging the flange to hold the door in latched position and in cooperation with the flange acting as a hinge, operating means inside the hood and operable from the outside thereof simultaneously to move the two pivoted brackets on one side to cause the hooks to move out of contact with the flange to enable the hood door to be raised, the hooks of the pivoted brackets and the flange at the other hood side acting as a hinge.

3. In a latch for the hood door of an automotive vehicle, a stationary part of the vehicle on which the door rests in closed position, an inwardly directed flange at each side edge of the hood door where it rests on the stationary part

of the vehicle, brackets mounted interiorly of the hood on the side of said stationary part at both sides of the hood, movable brackets pivoted to the first brackets, a hook on each movable bracket capable of engaging the flanges to hold the door in latched position, operating means inside the hood at both sides thereof to move the pivoted brackets to cause the hooks to move into contact with the flanges to latch the hood door or out of contact therewith to enable the hood door to be raised either at one side or at both sides, means outside the vehicle to operate

said operating means, pilots mounted in said stationary part at the edges of the hood door, the flanges of said door having openings to receive the pilots, said pilots and openings causing the door to seat accurately to enable the engagement between the hooks and the hood flanges, and means on the pilots engageable by the door to limit the extent of movement of the door when raised on one side only.

10
